UNITED STATES PATENT OFFICE

JOSEPH WILLIAM ISHERWOOD AND WILLIAM ISHERWOOD, OF RAGGLES WOOD,
CHISLEHURST, ENGLAND

HATCH COVER

Application filed December 11, 1931, Serial No. 580,448, and in Great Britain January 15, 1931.

I have filed application in Great Britain January 15, 1931.

This invention relates to hatch covers for floating vessels and has for its object to provide an improvement over the constructions disclosed in our U. S. Letters Patent No. 1,679,526 granted August 7, 1928 entitled "Hatch cover".

According to the present invention the sections of the cover are adapted to so cooperate with one another that when one of them is prevented from lateral movement, the remainder are thereby held in locked position. This is brought about by constructions simple in operation and cheap in manufacturing costs.

In one way of carrying out the invention, some of the hatch sections are provided with slots or recesses, or with projections forming locking pieces adapted to be engaged and thereby secured by projections forming locking pieces, or slots or recesses on fixed parts of the hatch such for example as the hatch webs and coaming when the hatch sections are moved into position, and means are provided for normally preventing these hatch sections from moving out of position. This may be effected by the other hatch section or sections, or by a bar or other filling piece.

Preferably the hatch section or sections, or the bar or other filling piece, is or are provided with means for locking it or them in position.

In a modification some of the hatch sections are held in position by adjoining hatch sections which are secured when moved into position. For this purpose some of the sections may be provided with projections forming locking pieces which engage slots or recesses in other sections.

Referring to the accompanying drawings forming a part of this specification in which like reference characters designate like parts in all the views, as for example A represents the sections of which a hatch cover is formed, B represents the webs for supporting the sections, C represents the hatch coaming, and so on as will be clear from the following description;—

Fig. 1 is a top plan view of one of the sections of which a hatch cover is formed;

Figs. 2 and 3 are respectively a partial side elevation and an end elevation of the cover section illustrated in Fig. 1;

Fig. 4 is a diagrammatic top plan view of a hatch opening illustrating the application of a plurality of cover sections to close the same, several of the sections being absent and other of the sections being shown fragmentarily in order to show the webs for supporting the sections;

Fig. 5 is a diagrammatic vertical sectional view through the hatchway and taken parallel to one of the supporting webs;

Fig. 6 is a diagrammatic vertical sectional view through the hatchway and taken at right angles to the supporting webs;

Fig. 7 is an enlarged detail in section of the support and locking arrangement, on a web, of the ends of two adjoining cover sections;

Fig. 8 is a fragmentary diagrammatic side elevational view of one of the webs and particularly illustrating thereon a plurality of wedge-shaped engaging pieces for holding the several cover sections in locked position;

Fig. 9 is a fragmentary perspective view in detail of a locking member 4 carried by a web and its slidable relation to a locking attachment 1 carried by a cover section;

Figs. 10, 11 and 12 are respectively a side elevation, a transverse section, and a top plan view of the member 4 shown in Fig. 9 in full locking position;

Fig. 13 is a view similar to Fig. 11 but taken through the pivotal catch for preventing displacement out of the locking member 4;

Fig. 14 is a perspective detail view of the end of a cover section in which has been cut a T shaped slot for engagement with a locking member carried by a web;

Fig. 15 is a vertical sectional view taken transversely through a web and illustrating the engagement referred to in the description of Fig. 14;

Fig. 16 is a side elevational detail of a web illustrating the locking member secured

thereto and its relation to the T shaped slot of an engageable cover section;

Figs. 17, 18 and 19 are views similar respectively to Figs. 14, 15 and 16 but illustrating the coaction of the web-carried locking member with a modification of the T shaped slot construction carried by a cover section;

Fig. 20 is a view somewhat similar to Fig. 9 but illustrating a slidable locking member of 10 dumb-bell formation and engageable with a T shaped slot on the end of a cover section;

Figs. 21, 22 and 23 are details more clearly showing the locking engagement of the parts mentioned in the description of Fig. 20;

15 Figs. 24 and 25 are detail views showing modifications of the slot construction illustrated respectively in Figs. 14 and 17;

Figs. 26 and 27 are views similar to Figs. 10 and 13 but illustrating a modification of 20 the pivotal catch construction on the web-carried locking member;

Fig. 28 illustrates a different means of securing the cover sections in engagement with the web-carried lugs 2 illustrated in Fig. 8;

25 Figs. 29, 30 and 31 are views clearly showing mortise and tenon modified engagement of two adjacent cover sections, particularly useful in smaller hatchways and according to which the lugs 1, 2 may be eliminated are 30 materially reduced in number; and

Figs. 32 to 39 inclusive are detail views illustrating various modified forms of construction enabling the cover sections to be slid readily into position, said views further 35 showing a separate channel member removable from the web and carrying the locking members and/or securing lugs 2 engageable with the cover sections.

Referring more particularly to Figures 40 1-8, the sections A are formed with one or more stiffening grooves, b as desired, and suitable lifting means. Attachments 1, preferably wedge-shaped lugs, are secured to the sections, and in order that the sections may 45 be interchangeable, the wedges or lugs are preferably sloped in both directions, as shown.

Referring now to Figures 4-8, on hatch webs B and/or on the hatch coamings C, correspondingly wedge-shaped engaging pieces 50 2 are secured so that when the closing section on each bay D is placed in position, and preferably locked by a locking arrangement, 55 the whole of the covers are thereby held in locked position.

In Figures 9-13 there is illustrated one form of locking device: In this construction the webs B are provided with slots 3 in which 60 65 wedge-shaped locking pieces 4 are slidably mounted, in such a manner that they can be moved into position to cooperate with the locking pieces 1 on the closing section. In order to hold the locking pieces 4 in locked and unlocked positions, pivoted locking

catches 5 are provided, which drop into slots 6, 7 in the webs B or the coaming C.

Figs. 14-16 show an arrangement in which one or more flanges or ends of the sections have T-shaped slots 6', and the pieces 70 2 are suitably shaped to enter and engage these slots, so that the covers may be slid in either direction into wedged holding position.

Alternatively, in place of forming the slots 75 in the flanges, attachments 8 may be secured to the flanges of the covers, see Figures 17-19, the attachments 8 having the slots 6' formed therein, thus creating a pocket for the reception of the engaging pieces 2.

The closing sections are held in locked position by locking pieces 9 which are slidably mounted in slots 3 in the webs B or coaming C, see Figures 20-23. It should be observed that this securing of the closing section may be accomplished either through 85 parallel locking as shown in Figure 20, or cam-locking as shown in Figure 21.

In the modification shown in Figures 24 and 25, the T-shaped slots 6' are replaced 90 by L-shaped grooves 10, which are formed in the flanges of the sections as shown in Figure 24, or are formed in attachments 8 secured to the flanges as shown in Figure 95 25. The closing section may be similar to that shown in Figure 9 and therefore may, in this construction, be locked by the arrangement shown in Figures 9-13, or it may be locked by the arrangement shown in Figures 26-27 wherein the pivoted latch 5 is 100 replaced by a vertically slidable drop latch or yoke 5'.

In the modification shown in Figure 28 the attachments 1 on all the sections A engage fixed pieces 2 on the webs B or coaming C and, after being engagingly positioned, are prevented from moving, i. e. are held in locked position, by means of locking bars 11 which are dropped between any two adjacent sections or between the ends of the sections and the coaming. These bars may be provided with any convenient locking means, such as a locking bolt.

In the modification shown in Figures 29-31, some of the sections have slots formed 115 in one side flange to be engaged by projecting tongues 12 on the adjacent sections. In this modification there is no necessity to provide locking pieces 1 on these sections, nor their corresponding pieces 2, since they interlock with each other.

In order to enable the sections to be slid into position as, for example, from the center of the hatch to the side coamings, or vice versa, the modified arrangements shown in 125 Figures 32-39 may be employed, in which the webs B and/or coamings C are provided with guide pieces for the sections, and in which the pieces 2 are formed on a member 130 which can be removed.

In Figures 32 and 33, the pieces 2 are secured to channel members 13 which can be removed from the webs and/or coamings, and the webs and/or coamings are provided with guide pieces 14 which guide the sections while they are being slid into position.

In Figure 34, in place of providing the guide pieces 14, the flanges of the sections are cut away as indicated at 15 for positioning on the webs B.

In Figures 35 and 36, guide pieces 16 are provided which are recessed to accommodate tongues 17 on the sections. In this arrangement the tongues are formed by cutting away the flanges of the sections. In Figure 37 the tongues are formed as separate members secured to the flanges of the sections and may, as shown in Figure 38, be enlarged at their outer edge. In Figure 39 the tongues are formed on the pieces 1.

It is obvious that those skilled in the art may vary the details of construction as well as arrangements of parts without departing from the spirit of the invention, and therefore it is not desired to be limited to the foregoing except as may be required by the claims.

What is claimed is:

1. In a hatch provided with framing the combination of a cover comprising a plurality of small sections two of which constitute closing sections; and cooperating wedging means carried by the sections and the hatch framing for holding the sections in place, one of said means slidable and provided with a transversely operable latch for locking all of said sections.

2. In a hatch provided with coaming and web framing the latter dividing the hatchway into bays the combination of a cover comprising a plurality of sections with a closing section for each bay, each section provided with means for holding it in place relative to the coaming and the framing; stationary means on the coaming and the framing for co-engagement with the holding means of the sections other than the closing sections; slid- able means on the coaming and the framing cooperating with the holding means of the closing sections for securing all of said sections in place; and means operable transversely of the slidable means to lock the latter.

3. In a hatch provided with coaming and web framing the latter dividing the hatchway into bays the combination of a cover comprising a plurality of sections with a closing section for each bay, each section provided with means for holding it in place relative to the coaming and the framing; stationary means on the coaming and the framing for co-engagement with the holding means of the sections other than the closing sections; and slidable means on the coaming and the framing cooperating with the holding means of the closing sections for securing all of said

sections in place, the slidable means on the framing adapted for simultaneous cooperation with two closing sections.

4. In a hatch provided with coaming and web framing the latter dividing the hatchway into bays the combination of a cover comprising a plurality of sections with a closing section for each bay, each section provided with means for holding it in place relative to the coaming and the framing; stationary means on the coaming and the framing for co-engagement with the holding means of the sections other than the closing sections; and slidable means on the coaming and the framing cooperating with the holding means of the closing sections for securing all of said sections in place, the slidable means on the framing adapted for simultaneous cooperation with a plurality of closing sections.

5. In a hatch provided with coaming and web framing the latter dividing the hatchway into bays the combination of a cover comprising a plurality of sections with a closing section for each bay, each section provided with means for holding it in place relative to the coaming and the framing; stationary means on the coaming and the framing for co-engagement with the holding means of the sections other than the closing sections; and slidable means on the coaming and the framing cooperating with the holding means of the closing sections for securing all of said sections in place, the slidable means on the framing mounted in a slotway and adapted for simultaneous cooperation with two closing sections.

6. In a hatch the combination of a framing element extending across the hatch; a cover comprising a plurality of sections arranged in rows on opposite sides of and supported by said framing element, each row containing a closing section for holding the sections of that row in place; and a member slidably mounted on said framing element to engage simultaneously the closing sections of adjacent rows to lock all of the sections therein.

7. In a hatch the combination of a framing element extending across the hatch and provided with a slot; a cover comprising a plurality of sections arranged in rows on opposite sides of and supported by said framing element, each row containing a closing section for holding the sections of that row in place; and a member slidably mounted in the slot of said framing element and provided with enlarged ends disposed on opposite sides of said element, said ends to engage simultaneously cooperating locking portions on the closing sections of adjacent rows to lock all of the sections therein.

8. In a hatch the combination of a framing element extending across the hatch and provided with a slot; a cover comprising a plurality of sections arranged in rows on

opposite sides of and supported by said framing element, each row containing a closing section for holding the sections of that row in place; and a member slidably mounted on 5 said framing element to engage simultaneously the closing sections of adjacent rows to lock all of the sections therein; said member having a central portion of reduced dimension engaging said slot.

10. 9. In a hatch the combination of a framing element extending across the hatch and provided with a slot; a cover comprising a plurality of sections arranged in rows on opposite sides of and supported by said framing element, each row containing a closing section for holding the sections of that row in place; and a substantially dumb-bell shaped member slidably mounted in the slot of said framing element, the enlarged ends 15 disposed on opposite sides of said element, said ends to engage simultaneously cooperating locking portions on the closing sections of adjacent rows to lock all of the sections therein.

25. 10. In a latch the combination of a framing element extending across the hatch and provided with a slot; a cover comprising a plurality of sections arranged in rows on opposite sides of and supported by said framing element, each row containing a closing section for holding the sections of that row in place, each closing section having a bayonet slot at one end thereof; and a substantially 30 dumb-bell shaped member slidably mounted in the slot of said framing element, the enlarged ends disposed on opposite sides of said element, said ends to engage simultaneously the bayonet slots of the closing sections of adjacent rows to lock all of the sections therein.

40. 11. In a hatch the combination of a framing element extending across the hatch and provided with a slot; a cover comprising a plurality of sections arranged in rows on opposite sides of and supported by said framing element, each row containing a closing section for holding the sections of that row in place, each closing section having a bayonet slot at one end thereof; and a substantially 45 dumb-bell shaped member slidably mounted in the slot of said framing element, the enlarged ends disposed on opposite sides of said element, said ends having surfaces to engage simultaneously and cooperatively 50 corresponding surfaces of the closing sections of adjacent rows to lock all of the sections therein.

55. 12. In a hatch the combination of a framing element extending across the hatch and provided with a slot; a cover comprising a plurality of sections arranged in rows on opposite sides of and supported by said framing element, each row containing a closing section for holding the sections of that row in place, each closing section having a bayo- 60

net slot at one end thereof; and a substantially dumb-bell shaped member slidably mounted in the slot of said framing element, the enlarged ends disposed on opposite sides of said element, said ends having inclined 70 surfaces to engage simultaneously and wedgely the similarly formed corresponding surfaces of the closing sections of adjacent rows to lock all of the sections therein.

13. In a hatch the combination of a framing element extending across the hatch and provided with a slot; a cover comprising a plurality of sections arranged in rows on opposite sides of and supported by said framing element, each row containing a closing section for holding the sections of that row in place; a substantially dumb-bell shaped member slidably mounted in the slot of said framing element, the enlarged ends disposed on opposite sides of said element 80 to engage simultaneously the closing sections of adjacent rows to lock all of the sections therein; and a latch transversely operable of the slidable member to secure the latter in locking position.

14. In a hatch the combination of a framing element extending across the hatch and provided with a slot; a cover comprising a plurality of sections arranged in rows on opposite sides of and supported by said framing element, each row containing a closing section for holding the sections of that row in place; a substantially dumb-bell shaped member slidably mounted in the slot of said framing element, the enlarged ends disposed 95 on opposite sides of said element to engage simultaneously the closing sections of adjacent rows to lock all of the sections therein; and a latch transversely operable of the slidable member to secure the latter in locking position.

15. In a hatch the combination of a framing element extending across the hatch and provided with a slot; a cover comprising a plurality of sections arranged in rows on opposite sides of and supported by said framing element, each row containing a closing section for holding the sections of that row in place; a substantially dumb-bell shaped member slidably mounted in the slot of said framing element, the enlarged ends disposed 110 on opposite sides of said element to engage simultaneously the closing sections of adjacent rows to lock all of the sections therein; and a latch mounted upon one of 115 said enlarged ends but transversely operable of the slidable member to secure the latter in locking position.

16. In a hatch the combination of a framing element extending across the hatch and provided with a slot; a cover comprising a plurality of sections arranged in rows on opposite sides of and supported by said framing element, each row containing a closing 120

section for holding the sections of that row in place; a substantially dumb-bell shaped member slidably mounted in the slot of said framing element, the enlarged ends disposed 5 on opposite sides of said element to engage simultaneously the closing sections of adjacent rows to lock all of the sections therein; and a latch pivotally mounted upon one of said enlarged ends but transversely operable 10 of the slidable member to secure the latter in locking position, said latch engageable with said element.

17. In a hatch the combination of a framing element extending across the hatch and 15 provided with a slot; a cover comprising a plurality of sections arranged in rows on opposite sides of and supported by said framing element, each row containing a closing section for holding the sections of that 20 row in place; a substantially dumb-bell shaped member slidably mounted in the slot of said framing element, the enlarged ends disposed on opposite sides of said element to engage simultaneously the closing sections 25 of adjacent rows to lock all of the sections therein; and a latch comprising a slidable yoke, said latch engageable with said element and transversely operable of the slid- 30 able member to secure the latter in locking position.

18. In a hatch the combination of a framing element extending across the hatch and provided with a slot; a cover comprising a 35 plurality of sections arranged in rows on opposite sides of and supported by said framing element, each row containing a closing section for holding the sections of that row in place; a substantially dumb-bell shaped member slidably mounted in the slot 40 of said framing element, the enlarged ends disposed on opposite sides of said element to engage simultaneously the closing sections of adjacent rows to lock all of the sections therein; and a latch comprising a slid- 45 able yoke mounted upon the enlarged ends and transversely operable of the slidable member to secure the latter in locking position, said yoke bridging said element.

19. In a hatch the combination of framing; 50 a hatch cover comprising a plurality of sections, the framing and the sections provided with cooperating holding means, said sections arranged in groups, each group includ- 55 ing a closing section for maintaining said means operable, one end of each closing section provided with a surface which when engaged will secure that section to said framing; and a member slidably mounted on said framing to engage simultaneously the surfaces of two closing sections to lock all of 60 said sections.

20. In a hatch the combination of a cover 65 comprising a plurality of small sections arranged in plural groups, a section in each group constituting a closing section; station-

ary means for holding the sections of a group other than the closing section; and slidable means engaging the closing sections of a plurality of groups for securing the remaining sections of said plurality of 70 groups.

21. In a hatch the combination of a cover comprising a plurality of small sections arranged in plural groups, a section in each group constituting a closing section; stationary wedging means for holding the sections of a group other than the closing sections; and slidable means wedgingly engaging the closing sections of a plurality of groups for securing the remaining sections of said plurality of 80 groups.

22. In a hatch provided with coaming and framing the combination of a cover comprising a plurality of small sections arranged in plural groups, a section in each group constituting a closing section, each of said sections provided at an end with means for holding the section in place; stationary means for holding the sections other than the closing sections, said means carried by 90 the coaming and the framing and adapted to coact with the ends of said sections; and slidable means engaging the ends of the closing sections of a plurality of groups for securing the remaining sections of said plurality of 95 groups, said slidable means likewise carried by the coaming and the framing.

23. In a hatch the combination of a cover comprising a plurality of small sections arranged in plural groups, a section in each 100 group constituting a closing section; stationary means for holding the sections of a group other than the closing section; slid- 105 able means engaging the closing sections of a plurality of groups for securing the remaining sections; and means for locking the slidable means.

24. In a hatch the combination of a cover comprising a plurality of small sections arranged in plural groups, a section in each group constituting a closing section; stationary means for holding the sections of a group other than the closing section; slid- 110 able means engaging the closing sections of a plurality of groups for securing the remaining sections; and pivoted means carried by the slidable means for locking the latter.

25. In a hatch the combination of a cover comprising a plurality of small sections two of which constitute closing sections; and plural means one of which is slidable for locking all of said sections together, the slidable means adapted for simultaneous co- 120 operation with the two closing sections. 125

26. In a hatch the combination of a cover comprising a plurality of small sections two of which constitute closing sections; plural means one of which is slidable for locking all of said sections together, the slidable 130

means adapted for simultaneous cooperation with the two closing sections; and means operable transversely of the slidable means for locking the latter.

- 5 27. In a hatch the combination of a cover comprising a plurality of small sections two of which constitute closing sections; plural wedging means one of which is slidable for locking all of said sections together, the slidable means adapted for simultaneous cooperation with the two closing sections; and pivoted means carried by the slidable means and operable transversely thereof for locking the latter.
- 10 28. In a hatch the combination of a cover comprising a plurality of small sections two of which constitute closing sections; plural wedging means one of which is slidable for locking all of said sections together, the slidable means adapted for simultaneous cooperation with the two closing sections; and pivoted means carried by the slidable means and operable transversely thereof for locking the latter.
- 15 29. In a hatch the combination of a cover comprising groups of small sections, a section in each group constituting a closing section; and stationary and movable wedging means for engaging the sections of each group, the movable means operating upon the closing sections to lock all of said sections in place and adapted for simultaneous cooperation with two closing sections.
- 20 30. In a hatch the combination of a cover comprising groups of small sections, a section in each group constituting a closing section; stationary and movable wedging means for engaging the sections of each group, the movable means operating upon the closing sections to secure all of said sections in place and adapted for simultaneous cooperation with two closing sections; and means for locking the movable means said locking means operable transversely of the
- 25 31. In a hatch provided with framing the combination of a cover comprising a plurality of small sections two of which constitute closing sections; and wedging means for holding all of said sections to the hatch framing, one of said means slidable for locking all of said sections and adapted for simultaneous cooperation with the two closing sections.
- 30 32. In testimony whereof we affix our signatures.
- 35 JOSEPH WILLIAM ISHERWOOD.
WILLIAM ISHERWOOD.
